(57) **CLAIM**

The ornamental design for a wine tumbler with lid, as shown and described.

DESCRIPTION

FIG. 1 is a top perspective view of a wine tumbler with lid embodying my new design, with the tumbler being made from a stainless steel material and the lid from a plastic material;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

The shading lines only help to show the shape and do not depict any surface decoration.
